Letters Patent No. 397, dated July 15th 1851

The schedule referred to in these Letters Patent and making part of
the same

To all whom it may concern

Be it known that I, Elijah P. Penman of the city of Rochester in the
County of Monroe and State of New York have invented and produced
a new and original design for Stoves and I do hereby declare
that the following is a full and exact description of the same.
Reference being had to the specimen and accompanying drawings
figured. Figure 1 is a section showing the end view of figure 3.
O.P. represents the carving on the horizontal surface.

What I claim as my invention and desire to secure by Letters Patent
is the ornamental design or production represented by figures 2 and
4 to be used with the carving represented by letter O.P.
